[57] CLAIM

The ornamental design for a package, as shown and described.

DESCRIPTION

FIG. 1 is a front perspective view from above of the package of the present invention;

FIG. 2 is a rear perspective view from below of the package of FIG. 1;

FIG. 3 is a top perspective view of the package of FIG. 1 shown in an open, flat configuration;

FIG. 4 is a sectional showing of a portion of the package of FIG. 3 taken through the lines X—X thereof; and,

FIG. 5 is an enlarged, fragmentary view of the hinged portion of the package of FIG. 3 shown generally in the direction of view of arrow Y.
